UNITED STATES PATENT OFFICE.

HENRY L. MILLIS, OF MILLIS, MASSACHUSETTS.

DESIGN FOR A CAMPAIGN HORN.

SPECIFICATION forming part of Design No. 21,789, dated August 23, 1892.

Application filed July 22, 1892. Serial No. 440,961. Term of patent 14 years.

To all whom it may concern:

Be it known that I, HENRY L. MILLIS, of Millis, in the county of Norfolk and State of Massachusetts, have invented a new and original Design for Campaign Horns, of which the following is a specification.

The drawing represents a side view of a campaign horn, showing my design.

The leading feature of my design consists in three broad encircling bands of contrasting colors, one band having stars.

In the drawing, *a* designates an encircling band of a particular color, which may cover about one-third of the outer surface of the horn at one end thereof.

b is an encircling band of a color differing from that of the band *a*, centrally located and also covering about one-third of the outer surface of the horn.

c is an encircling band covering the balance of the outer surface of the horn and of a color contrasting with that of the bands *a* and *b*.

d designates stars located on the band *c*.

What I claim is—

The design for a campaign horn, as herein shown and described.

In testimony whereof I have signed my name to this specification, in the presence of two subscribing witnesses, this 19th day of July, A. D. 1892.

HENRY L. MILLIS.

Witnesses:

ARTHUR W. CROSSLEY,
A. D. HARRISON.
